DESIGN FOR A CASE FOR DRILL BITS OR
OTHER SLENDER ARTICLES

Richard Linneman, Atlanta, Ga.

Application August 6, 1947, Serial No. 140,732

Term of patent 14 years

(CL. D80—5)

To all whom it may concern:

Be it known that I, Richard Linneman, a citizen of the United States of America, residing at 542 Courtland Street, N. E., Atlanta, Georgia, have invented a new, original, and ornamental Design for a Case for Drill Bits or Other Slender Articles, of which the following is a specification, reference being had to the accompanying drawing, forming part thereof, wherein

Figure 1 is a perspective view of a case for drill bits or other slender articles, showing my new design;

Figure 2 is a side elevation;

Figure 3 is an end view; and

Figure 4 is a plan view.

I claim:

The ornamental design for a case for drill bits or other slender articles, as shown.

RICHARD LINNEMAN.
